UNITED STATES PATENT OFFICE.

JOHN S. STOTT, OF READING, PENNSYLVANIA.

AUTOMATIC NAIL-PLATE FEEDER.

SPECIFICATION forming part of Letters Patent No. 358,231, dated February 22, 1887.

Application filed January 25, 1886. Serial No. 189,717. (No model.)

To all whom it may concern:

Be it known that I, JOHN S. STOTT, a citizen of the United States, residing at the city of Reading, county of Berks, State of Pennsylvania, have invented a new and useful Improvement in Automatic Nail-Feeders, of which the following is a specification.

This invention relates more particularly to the class of machines ordinarily used in nail factories.

The object of the invention is to furnish ready for attachment to the ordinary hand-operated nail-cutting machines an apparatus which will take the place of the skilled operative, and which will automatically feed the nail-plate to the shear in the same manner that it is done by hand.

The improvement is simple in its parts, not liable to get out of order, is easily adjusted to any machine adapted thereto, and is inexpensive to construct.

The drawings herewith fully show my improvement in detail, enough of the machine being introduced to show the connection of the feeder therewith.

Like letters of reference indicate like parts throughout.

Figure 1 is a side elevation of an ordinary nail-machine with my automatic feeder attached. Fig. 2 is an end view of the machine.

Fig. 3 represents a plan of the automatic nail-feeder bed. Fig. 4 represents in plan and side elevation the cradle-piece for the reciprocating nose-barrel cradle. Fig. 5 is a plan, side

35 elevation, and end view of the cradle for the reception of the nose-barrel. Fig. 6 represents the nose-barrel in side elevation and plan.

Fig. 7 represents the grip in front, side elevation, and plan. Fig. 8 represents the rocking yoke, lever-arm, and supporting-frame for

giving a vertical movement to the cradle-piece, cradle, and nose-barrel. Fig. 9 represents in front elevation and plan the oscillating belt-yoke by which a reciprocating semi-revolution is given to the nose-barrel; Fig. 10, an enlarged front and side elevation of the tension-pieces hinged to the belt-yoke arms.

Fig. 11 represents in plan and side elevation the hook-an-eye attachment of the belts to the 45 nose-barrel.

In the drawings, A represents the bed of the

nail-machine; A', caps to the main shaft; B, the legs of the machine; C, the main shaft; C', cam for operating the shear-lever; C², cam for raising the cradle-piece and cradle and 55 withdrawing the nose of the barrel from the shear-blades; C³, knocker for operating the grip; D, a pinion outside of the bed; E, a gear-wheel upon the counter-shaft; E', shaft running in bearings E², a fly-wheel, F, equalizing the motion of the main shaft; E³, a crank-wheel on the extremity of the counter-shaft. The machine is driven from a pulley suitably placed upon the main shaft.

My invention comprises, in combination with 55 a bracket, G, having a center set-screw, G', secured to the bed at the rear of the machine, a hinged bearing bracket-piece, H, at the front of the machine, secured to the bed by a screw, H', and having an ear, H², for a center screw, 70 H³, and a hinge-post, H⁴.

A horizontal shaft, I, provided with centers, is held beneath the bed upon the center screws, G' and H³, and has upon its rear outer end an arm, I¹, with hub I², and set-screw I³, with a 75 ball-seat head, I⁴, and cap I⁵, and at the opposite end a belt-yoke, J, with hub J¹, set-screw J², yoke J³, arms J⁴, center pivots, J⁵, and, suspended thereby, tension-pieces K, hinged at K' to the arms J⁴, having belt-hook K², notched 80 recesses K⁴, bolt-slot K⁵, nuts K⁶, and latches K⁷.

A feeder-bed, L, is hinged at L' to the post H⁴, having a downward-projected ear, L², with an adjusting angle-screw, L³. At the front it is provided with a check-post, L⁴, check-screw L⁵, and ears L⁶, for the support upon pivot-screws L' of the grip-piece. Said feeder-bed also has a seat, L⁷, for the supporting-arm S of the cradle-piece R, and a spring, M, connected to the check-post, and having its free 85 end connected with the pinching-arm of the grip.

The belt-yoke J, secured adjustably to the shaft I, passes up through an opening, H⁵, in the bracket H. Upon the enlarged base of 95 said bracket is supported a frame consisting of a base, N, and side posts, N', within which is hung a yoke, O, having a central arm, O¹, a link, O², and compound link and lever O³. The upper end of the lever is provided with a series of holes, O⁴, and is connected by a suitable rod, P, pin P', and nut P² to the top of an 100

arm, Q, pivoted at its lower end in a bearing, Q', secured to the bed of the machine. This lever in its normal condition lies against the cam C², and has a vibratory motion given it by the revolution of the shaft C, which motion, by the rod P, is transferred to the lever O³ and arm O'. A cradle-piece, R, by ears R', is supported upon the arm O' of the yoke O by a pintle-bolt, and at the opposite or front end it rests upon the piece S, bearing in seat L⁸, and is removably secured thereto. Hinge-ears R², by a pintle-bolt, connects the cradle-piece with the cradle T, which is provided with a hinge-joint, T', bearings T', cap T', and locking-pin or equivalent T'. A rest, U, is provided for the nipper-rod.

The barrel V revolves freely in the bearings T', and the nose V' is provided with the usual springs, V², and clamps V³. Collars V' serve to 20 retain the barrel in place.

The grip-piece is composed of a vertical arm, W, with a horizontal hub, W', head W², and projected seat W³. The hub is supported in the ears L⁶ upon the pivot-screws L⁷. Upon 25 the projected seat W³ is pivoted the grip W⁴, having a pinching-arm, W⁵, the outer end of which is connected in a suitable manner, by rod and eyes W⁶, to the grip-arm, and by nut W⁷ to a vertical arm, X, pivoted against the 30 inside of the bed at X', and which is given at the proper time a vibratory movement by a knocker, C³. This motion, being transferred to the pinching-arm W⁵, causes the head W⁴ to grip the nipper-rod and at the same time to 35 pull the grip-piece itself rearward by the rod W⁶, thus passing sufficient length of nail-plate within the shear to make the nail. As the grip-piece is drawn rearward the spring M, connected with the arm W⁵, is also pulled rearward, and the moment the knocker C³ passes by the arm X the resilience of the spring M returns the grip-piece in place ready for a 40 repetition of the movement, the check-bolt L¹ regulating the distance to which the barrel 45 nose-piece shall be withdrawn from the shear-blades.

The nose-piece V' of the barrel V is flattened and cored, so as freely to pass the size of nail-plate to be fed to the machine, and the 50 springs V² securely hold the plate until the grip operating forces the same beyond the ends of the springs a sufficient distance to allow for the production of the nail.

It is well understood that if the nail-plate 55 were fed to the shear-blades without reversal the result would be a nail with parallel sides, whereas the nail should be of a regular taper in width from head to point. To obtain this result the barrel V is given a reciprocating 60 semi-revolution in the cradle, alternating with the rearward movement of the nipper-rod and the reciprocating vertical movement of the rear end of the cradle-piece. The vertical movement is derived from the yoke-arm O', lever O³, rod P, arm Q, and cam C², and the 65 semi-reciprocating revolution from bands Y, hooks Y', and eyes Y², suitably secured to the

barrel V upon opposite sides of the same, passing from one arm, J⁴, over the barrel and beneath the same, rising to and being secured to 70 the barrel on its horizontal diametrical line, and from the opposite arm passing beneath the barrel, returning over the top, and descending to the same diametrical line, and similarly attached to the barrel. 75

The terminal ends of the belts or bands Y are connected with the tension-hooks K² of the suspension-pieces K, and adjustable for tension by the threaded portion K³ and nuts K⁴, the pieces K being held releasably in place 80 by pins K' and latches K'.

The yoke receives its reciprocating vibratory motion from the arm I², which, by its ball-seat connection with the rod Z to the crank E³, transfers the motion to the shaft I 85 and the yoke J, and as the latter oscillates transversely across the bed it alternately pulls upon the belts Y by its connection with the tension-hooks K², suspended from the arms J⁴, and thus imparts a semi-rotative movement 90 to the barrel.

The operation of the feeder is as follows: A piece of nail-plate is secured in the nipper-rod and inserted in the barrel with its end projected beyond the nose-springs, and the machine started. As the main shaft C revolves, the cam C' comes in contact with the lever-arm of the movable shear-blade and, elevating the arm, depresses the blade, and the first cut is made. The shear is now elevated by 100 the depression of the cam C' and cam C² in contact with arm Q, throws the same rearward, and by connection P, lever O³, and arm O' elevates the end of the cradle-piece R, and with it the cradle T, nose-piece V, nail-plate, 105 and nipper-rod, which, owing to the support of the cradle-piece at the front end upon the arm S, throws the nose and nail-plate away from the knife or shear. At the same moment the shaft I receives a reciprocating vibratory 110 motion from the arm I², connected by rod Z with the crank E³, and throws the belt-yoke J to one side or the other, as arranged, which, by its belt-connection Y with the opposite diametrical points of the barrel V, reverses the 115 position of the nail-plate relative to the shears. Then as the cradle-piece resumes its normal position of rest the grip W² W⁴ is brought into action by the knocker C³, operating the arm X, rod W⁶, and pinching-arm W⁵, which, 120 gripping the nipper-bar between the heads W² W⁴, pulls the same toward the shear the requisite distance, the shear is brought into action, and the cut is then a taper uniform from head to point. The revolutions being 125 continued, the plate will be cut alternately in uniform tapering widths, as is done by the machines which are hand-fed by operatives.

Being a practical nailer of many years' experience, I am well aware of what has been 130 successfully accomplished in this line of invention; but I believe my improvement to be a desirable departure from all prior automatic feeders in the positive attachment of the feeder,

in the elimination of momentum, in the support of the nose-barrel, the vibratory semi-revolution of the same, the adjustability and accessibility of the various parts, and the mode 5 of constructing and operating the nipper-rod grip of the same.

The barrel-cradle T is hinged to the cradle-piece R, for the purpose of enabling the knives of the shears to be taken out and replaced for 10 grinding or repairs without dismantling the entire automatic gear. The latches K⁷ are released from the tension-pieces K, and the lower ends thrown out from the arms J⁴, which relaxes the tension upon the belts Y and permits 15 the disengagement of the hooks Y' from the eyes Y² of the bands Y, when the barrel V, with its cradle T, is thrown around upon its hinge T² into the position shown in dotted lines in Fig. 1, leaving the shear-blades 20 entirely clear of obstruction from the feeder.

Having shown the construction, use, and advantages of my improvement, I desire to secure by Letters Patent the following claims upon the same:

25 1. In combination with the bed of a nail-machine and its rear bracket-piece, G, having a pivotal screw, G', the front bracket-piece, H, provided with an opening, H¹, ear H², pivotal screw H³, and hinge-posts H⁴, secured by bolt H' to the bed and suspended upon said pivotal screws, the shaft I, substantially as shown and described.

2. In combination with the front bracket, H, and its hinge-post H⁴, as described, and 35 pivoted thereto by joint L', the bed L, having a downward-projected arm, L², with adjusting-screw L³ at the end of the arm, a check-post, L⁴, with adjusting-screw L⁵ at its front end, a seat, L⁶, for the cradle-support S, ears L⁷, and pivotal screws L' for the support of 40 the grip W, and a spring, M, secured to the face of the check-post with its free end in contact with the arm W² of the grip, all arranged, combined, and adapted to be adjusted vertically by the screw L³, substantially as shown, and for the purpose set forth.

3. In combination with the bracket H and bed L of an automatic nail-feeder, as described, a cradle-piece, R, supported at its front end 50 upon the arm S, seated upon the bed L, connected at the rear end by ears R', with a vibrating arm, O', having ears R², within which is pivoted the hinge T² of the cradle T, adapted to carry the nose-barrel V, a locking-pin, T⁴, 55 or its equivalent, releasably securing the cradle to the cradle-piece, a nipper-rod rest, U, at the forward end holding the same in line with the grip, the arm O', with its lever O³, and frame N¹, suitably secured to the bracket 60 H, the lever O³, by rod P, arm Q, and cam C²,

imparting a vertical vibratory motion by arm O' to the rear end of the cradle-piece with cradle and nose-barrel thereon, substantially as and for the purpose set forth.

4. In combination with the bracket, bed, 65 cradle-piece, cradle, and nose-barrel of an automatic nail-feeder, as shown and described, a nipper-rod grip composed, essentially, of the following elements: an arm, W, with hub W', head W², and projected seat W³, supported upon the cradle-piece by pivotal screws L' in ears L⁶, and having pivoted upon said projected seat a grip-head, W⁴, with arm W⁵, said head being held free of the nipper-rod by the spring M, connected therewith, and being 70 drawn at proper intervals rearward by connections with arm X by rod W⁶ and knocker C³ of main shaft C, whereby the grip bites upon the nipper-rod and advances the same, with its nail-plate, through the barrel-nose 75 springs V² toward the shear, as and for the purpose set forth.

5. In combination with a shaft, I, supported in brackets G H by pivotal screws G' H³, receiving through arm I², rod Z, and crank E³ 85 a reciprocating semi-revolution, a yoke, J³, secured by hub J' and screw J² adjustably upon said shaft, having arms J⁴, and suspended therefrom on pins K', tension-pieces K, with hooks K², adjusting-nuts K⁶, and latches K⁷, connected to the barrel V by belts Y, hooks Y', and eyes Y², whereby the semi-revolution of the shaft I transmits a transverse reciprocating motion to the nose-barrel, nail-plate, and nipper-rod, substantially as and for the purpose declared. 95

6. In combination with a nail-machine, an automatic nail-feeder consisting, essentially, of the following elements in combination: an adjustable bed, L, hinged to bracket H, having 100 check-post, check-screw, spring M, cradle-support S, and grip W, with hub W', head W², and grip W⁴, with arm W⁵, cradle-piece R, cradle T, and nose-barrel V, all and severally deriving motion from rods P W⁶, connected 105 with arms Q and X by cam C² and knocker C³ of main shaft, and by shaft I, its arm I², rod Z, and crank E³ transmitting a reciprocating semi-revolution to the yoke J, transferred by belts Y to the nose-barrel V, the whole 110 combined, arranged, and adapted, as described, at suitable intervals to advance and withdraw the nail-plate from the shear, to lift and reverse the nose-barrel with the plate and nipper-rod, and to automatically continue said 115 operation, as and for the purpose set forth.

JOHN S. STOTT.
